United States Patent Office

Des. 220,044
Patented Mar. 2, 1971

220,044

EMERGENCY TELEPHONE LIGHT

Fred G. Sinclair, 1330 NE, 144th St.,
North Miami, Fla. 33161

Filed Nov. 14, 1969, Ser. No. 20,078

Term of patent 14 years

Int. Cl. D14—03

U.S. Cl. D26—14

FIG. 1

FIG. 2

FIG. 1 is a top perspective view of an emergency telephone light showing my new design;

FIG. 2 is a bottom perspective view thereof.

The broken lines are shown for illustrative purposes only and form no part of the claimed design.

I claim:

The ornamental design for an emergency telephone light, as shown and described.
